UNITED STATES PATENT OFFICE.

ALONZO B. WOODARD, OF HORNELLSVILLE, NEW YORK.

FENCING-STRAND.

SPECIFICATION forming part of Letters Patent No. 447,927, dated March 10, 1891.

Application filed December 26, 1890. Serial No. 375,825. (No model.)

To all whom it may concern:

Be it known that I, ALONZO B. WOODARD, a citizen of the United States, residing at Hornellsville, in the county of Steuben and 5 State of New York, have invented new and useful Improvements in Fencing-Strands, of which the following is a specification.

This invention relates to the type of fencing-strand described and shown in Letters 10 Patent No. 433,940, and has for its object to avoid passing the serpentine wires between the two spirally-twisted wires; to provide a novel connection of the serpentine wires with the twisted wires; to facilitate the manufacture by providing a construction whereby it 15 is possible to apply the serpentine wires to a pair of wires which have previously been twisted together; to avoid the necessity of twisting the two wires as the serpentine wires 20 are laid in looped form between the former; to provide a construction whereby the serpentine wires are coiled upon the exterior of the previously-twisted wires to bind the latter together, and finally to provide a novel, 25 durable, efficient, and ornamental wire fencing-strand, which can be conveniently manufactured by simplified machinery. To accomplish all these objects my invention involves the features of construction, the combination 30 or arrangement of parts, and the principles of operation hereinafter described and claimed, reference being made to the accompanying drawing, in which the figure is a view, on an enlarged scale, showing a portion of a 35 fencing-strand constructed according to my invention.

In order to enable those skilled in the art to make and use my invention, I will now describe the same in detail, referring to the 40 drawing, where—

The numerals 1 and 2 indicate two wires which are spirally twisted together throughout their length, and the numerals 3 and 4 indicate two serpentine wires which are so 45 relatively arranged as to form a series of curvilinear or oblong loops 5, successively arranged on the longitudinal twisted wires 1 and 2 in such manner that the latter extends centrally through the loops formed by the 50 wires 3 and 4. These loops are separated

from each other by portions of the serpentine wires, being coiled, as at 6, around the exterior of the spirally-twisted wires 1 and 2, by which construction the spirally-twisted wires are firmly bound together, while the looped 55 form of the serpentine wires is preserved and they are rigidly and permanently connected with the spirally-twisted wires by the coiled portions 6, above referred to.

In the manufacture of this improved fencing-strand the wires 1 and 2 can be spirally twisted together and subsequently the serpentine wires can be applied thereto. By this means the manufacture of the fencing-strand is materially facilitated and simplified 60 machinery rendered possible.

The serpentine wires at the commencement of the manufacture are first coiled upon the exterior of the spirally-twisted wires. They are then carried laterally in opposite directions to form a loop and are then brought toward the spirally-twisted wires, and the wires 3 and 4 are both carried in the same direction around the exterior of the spirally-twisted wires to form a coiled portion 6. The 65 operation is repeated for each looped portion 5, and by this means the loops are separated from each other by the coiled portions 6, which coiled portions, however, form integral 70 parts of the wires which form the loops.

The improved construction avoids the necessity of the complicated machinery rendered essential where the serpentine wires are carried between the spirally-twisted wires, as in the patent before alluded to, and, further, by coiling the serpentine wires upon the exterior of the spirally-twisted wires it is impossible for the looped portions of the wires 75 3 and 4 to move upon each other where they connect with the spirally-twisted wires, as can 80 occur in the former construction.

The present invention provides a fencing-strand which is strong, substantial, and ornamental, and can be manufactured by simplified machinery, thereby reducing its cost 85 of production while enabling it to be more conveniently manufactured by mechanical means.

Having thus described my invention, what I claim is—

A fencing-strand consisting of two longitudinal spirally-twisted wires and serpentine wires coiled at intervals around the exterior of the spirally-twisted wires and between 5 such coiled portions expanded into curvilinear or oblong loops, substantially as shown and described.

In testimony whereof I have hereunto set my hand and affixed my seal in presence of two subscribing witnesses.

ALONZO B. WOODARD. [L. S.]
